TO F. X. HOOPER COMPANY, OF GLENARM, MARYLAND, A CORPORATION OF MARY-
LAND.

BOX-FLAP-CUTTING MECHANISM.

Application filed July 5, 1924. Serial No. 724,494.

To all whom it may concern:

Be it known that we, ELLWOOD A. METZ and THOMAS S. FITCHETT, citizens of the United States, residing at Glenarm, in the 5 county of Baltimore and State of Maryland, have invented certain new and useful Improvements in Box-Flap-Cutting Mechanism, of which the following is a specification.

This invention relates to mechanism for 10 cutting the flaps of box blanks, and also for scoring the blanks. The invention is shown as an attachment to a press for printing upon such blanks, whereby the blanks may be printed, scored, and have their flaps 15 cut during their passage through the press. The attachment may, however, be used separately from the press, when provided with suitable feeding mechanism.

In carrying out the invention, we provide 20 parallel shafts carrying heads upon which are mounted the knives for cutting the flaps, and these shafts also carry heads having scoring segments for scoring the blanks. Through suitable gearing, these 25 shafts are timed to the movements of the shafts carrying the printing cylinders, and as the blanks leave the printing cylinders they are carried between the pairs of scoring and cutting heads, where the blanks are 30 scored and their alternate flaps are cut. The knives for cutting off the flaps are arranged upon pairs of heads at opposite sides of the attachment. One head of each 35 pair carries two relatively short segmental knives which, in practice, have two of their adjacent ends spaced apart circumferentially a distance substantially equal to the length of a flap on the box blank which is to be left uncut, and the other 40 head carries a relatively long segmental knife which is adapted to overlap the other knives and to co-operate therewith in cutting the flaps, one end of the relatively long knife, in the practical operation of 45 the machine, being circumferentially spaced from the end of one of the shorter knives, when the latter is at the cutting point, a distance equal to the length of a flap which is to be cut. Thus arranged, the knives

will cut the alternate flaps without cutting the intermediate flaps. The knives are adjustable about their axes and, by suitably setting the knives, flaps of various lengths may be cut, and the first and third, or the second and fourth flaps may be cut, as 55 desired.

In the accompanying drawing,

Fig. 1 is a side elevation of part of a printing press and the flap cutting and scoring attachment;

Fig. 2 is an end view of the same, looking from right to left in Fig. 1, parts being broken away;

Fig. 3 is a detail view, showing part of a cutter head, a knife and the clamping 65 means for the knife, in section;

Fig. 4 is a diagrammatic view illustrating the arrangement of the knives on the cutter heads for cutting the first and third flaps of a blank;

Fig. 5 is a plan view of a blank showing, in dotted lines, the cuts made by the knives when adjusted as in Fig. 4;

Fig. 6 is a diagrammatic view illustrating the arrangement of the knives on the 75 cutter heads for cutting the second and fourth flaps of a blank; and,

Fig. 7 is a plan view of a blank showing, in dotted lines, the cuts made by the knives when adjusted as in Fig. 6.

Referring to the drawing, *a* represents the frame of a printing press for printing on sheets of stiff material, such as strawboard, fiber, and the like, one of the printing cylinders being indicated at *b*, and an impression cylinder being indicated at *c*. The sheets to be printed upon, such as box blanks, are fed to the press by suitable feeding mechanism, not shown, and are carried along from left to right, in Fig. 1, on the 85 bed *1* of the press, by pull rollers, and after the impressions are made upon the blanks by the printing or form cylinders, they are carried by pull rollers to the flap cutting and off-set scoring devices which are 90 mounted on shafts *2* and *3*. These shafts are suitably mounted on a frame *d*, which is arranged at the delivery end of the print- 95

ing press. The pull rollers p , which are mounted on shafts 4 and 5 of the printing press, pass the blanks along to the pull rollers p' on shafts 6 and 7 on the frame d , and these pass the planks to the pull rollers p'' on shafts 8 and 9, from whence the blanks are passed to a delivery belt e . The power for operating the press is applied through a pulley 10^a to a shaft 10, having 10 a gear 11 which meshes with a gear 12 on a shaft 13, which carries the impression cylinder c . Upon this shaft, at the opposite side of the machine from that shown in the drawing, is a gear 14 which meshes with a 15 large idle gear 15, and the latter meshes with a large gear 16. The gear 16 engages a large gear 17 on a shaft 18, which carries the form cylinder b , and it also meshes with a gear 19 of the same diameter as 20 the gear 17, this gear 19 being secured to the shaft 2 which carries the upper cutter and scoring heads. The gear 19 engages a gear 20 which, in turn, engages a gear 21, and the gear 21 engages a gear 22^a on 25 the shaft 3, which carries the lower cutter and scoring heads. The shafts 2 and 3, which carry the cutter and scoring heads, are geared to turn at the same speed as the shaft 18, carrying the form cylinder. The 30 various pull rollers may be geared in any suitable way to the driving shaft. As shown, the pull roller shafts 4 and 5 on the press frame are driven through gears on said frame as follows: The pull roller 5 35 is operated from the driving shaft 10, through gears 23, 24 and 25; the pull roller shaft 4 is operated from the gear 24, through gears 26, 27, 28, and 29. The pull roller shafts 6, 7, 8, and 9 on the frame d of the cutting and scoring attachment are operated 40 from a gear 22 on the shaft 3. As shown, the pull roller 7 is operated from the gear 22, through gears 30 and 31, and the pull roller shaft 6 is operated from gear 23, through gears 30, 32 and 33. The 45 pull roller shaft 9 is operated from gear 22, through gear 34 meshing therewith, which gear is mounted upon a stud 35, and secured to the gear 34 is a larger gear 36, which meshes with gear 37 on the shaft 9. A gear 38, engaging the gear 36, drives a 50 gear 39 which, in turn, drives a gear 40 which meshes with a gear 41 on the pull roller shaft 8. Thus, the various pull rollers are driven in unison.

Upon the shaft 2 are mounted circular heads or wheels f, f' , which carry segmental off-set scoring members 42, adapted to co-operate with scoring rings or members on similar heads g, g' , mounted upon the shaft 3. These scoring members need not be particularly described, as they are well known. At the sides of the scoring heads f, f' , are heads h, h' , each of which carries two relatively short segmental cutters, indicated at

43 and 44. Upon the lower shaft 3 are arranged cutter heads j, j' , each of which carries a relatively long segmental cutter 45, arranged in shearing relation to the cutters on the heads h, h' , and adapted to 70 co-operate with the latter cutters in cutting off the alternate flaps of the box blanks as they pass between the cutter heads.

The knives are adjustably mounted in 75 grooves 46 in the cutter heads. As shown in the detail view Fig. 3, the knife 45 is arranged within a groove 46 which is formed by a flange 47 on the head h and a clamping ring 48 which is secured to said head and opposed to said flange. Each 80 cutter has a longitudinal recess 49 on one side, and a suitable number of clamping screws 50 extend through the ring 48 and into the adjacent recess 49 in the cutter, and when these screws are tightened, the knife 85 or cutter is held firmly in place. To adjust the cutter circumferentially about the head, the screws 50 may be loosened, and the knife or cutter may then be slid around in the groove 46 to any desired position of 90 adjustment and then clamped by tightening the screws.

The box blanks k , Fig. 5, are transversely slotted, as shown at 51, 52, and 53, before 95 they are fed into the printing press, and they pass endwise through the press and are printed upon and then pass between the upper and lower scoring and cutting devices. If the blanks pass between these 100 devices in the direction of the arrow, Fig. 4, and it is desired to cut off the ends of the first and third flaps 56 and 58 of the blank, the knives 44 on the cutter heads will be set so that their rear ends 44^a will be in line with the axes of the shafts 2 and 3 105 when the slots 51 in the blank are on this same line. The forward ends 43^a of the knives 43 will be spaced from the ends 44^a of the knives 44 a distance equal to the 110 distance between the centers of the slots 51 and 52, and the knives 45 will be set so that when the ends 43^a of the knives 43 are at the cutting point, in line with the axes of the shafts 2 and 3, the rear ends 45^a of the knives 45 will be spaced circumferentially a distance from the ends 43^a 115 equal to the distance between the centers of the slots 52 and 53 in the blank. The several knives are pre-set to suit the cutting of the blanks by the aid of suitable graduation marks on the heads.

With the knives arranged as shown in Fig. 4, when the blank k is fed in the direction of the arrow, the flaps 56 will be engaged by the forward or leading parts 120 of the knives 44 and 45 and the ends of the flaps 56 will be cut off along the dotted lines x . This cutting operation will cease when the ends 44^a of the knives 44 reaches the line joining the axes of the shafts 2 and 125 130

3, at which time the slots 51 will be on said line. As there is a gap between the ends 44^a and 43^a of the knives on the upper heads, only the lower knife will engage the 5 blank while the flaps 57 are passing the cutting point and therefore these flaps will not be cut. The ends 43^a of the knives 43 will be at the line joining the axes of the shafts 2 and 3 when the slots 52 are on 10 said line, and the knives 43 and 45 will then cut flaps 58 until the rear ends 45^a of the knives 45 reach the line joining the axes of the shafts 2 and 3, at which time the slots 53 will also be at said line and the 15 cutting operation will cease. As only the knives 43 will be in engagement with the blank when the flaps 59 are passing the cutting point, these flaps will not be cut.

If, instead of cutting the first and third 20 flaps on the blank, it is desired to cut the second and fourth, the knives will be adjusted as illustrated in Fig. 6; that is, the knives 43 and 44 will have their ends 43^a and 44^a spaced apart a distance equal to the 25 width of the flaps which are not to be cut, and the leading ends 45^b of the knives 45 will be arranged to overlap the rear ends 44^a of the knives 44 by a distance equal to the 30 width of the flaps which are to be cut. With this arrangement of the knives and proper timing of the feeding mechanism of the blank, when the first flaps 60 of the blank, Fig. 7, are passed between the cutting heads, only the leading portions of the knives 44 35 will engage the blank and these flaps will not be cut off. The leading ends 45^b of the knives 45 will then engage intermediate parts of the knives 44 and the knives will be in cutting engagement while the flaps 61 are 40 passing between the heads and these flaps will be cut off along the dotted lines x' . While the flaps 62 are passing between the heads, they will be engaged only by the knives 45 and will not be cut. When the 45 flaps 63 are passing between the heads, the leading ends 43^a of the knives 43 will engage the knives 45 at the slots 51^a, and these flaps will be cut along the dotted lines x' , (Fig. 7).

50 It will be evident that by adjusting the knives on the heads h relatively to one another, and by adjusting the knives 45 on the heads j relatively to the knives on the heads h , the knives may be arranged to cut off 55 flaps of various lengths and the knives may be caused to operate successively on the first and third flaps of a blank, or upon the second and fourth flaps, as desired.

For convenience in setting the knives to 60 cut the flaps, the heads on which the knives are mounted are, in practice, provided with graduation marks (not shown), so that the ends of the knives can be pre-set to cut alternate flaps of any given length.

65 As the blanks pass through the attach-

ment, the scoring members will effect off-set scoring, as indicated at y on the blanks.

By arranging the scoring and flap-cutting attachment at the delivery end of a press, and timing the movements of the scoring and cutting members to the movement of the printing cylinder or cylinders, a large saving in labor is effected, as the blanks do not have to be re-handled before being scored and cut. 75

What we claim is:

1. A machine for cutting the flaps of box blanks comprising two cutter heads geared to operate in unison, one having two relatively short spaced segmental knives, and the other having a relatively long segmental knife adapted to overlap both of said short knives. 80

2. A machine for cutting the flaps of box blanks comprising two cutter heads geared to operate in unison, one having two relatively short spaced segmental knives, and the other having a relatively long segmental knife adapted to overlap both of said short knives, said relatively long knife being adjustable about its axis to vary its relation to said other knives. 85

3. A machine for cutting the flaps of box blanks comprising two cutter heads geared to operate in unison, one having two relatively short spaced segmental knives adjustable about their axis relatively to one another, and the other having a relatively long segmental knife adapted to overlap both of said short knives. 95

4. A machine for cutting the flaps of box blanks comprising two cutter heads geared to operate in unison, one having two relatively short spaced segmental knives adjustable about their axis relatively to one another, and the other having a relatively long segmental knife adapted to overlap both of said short knives and adjustable about its axis to vary its relation to said latter knives. 105

5. A machine for cutting the flaps of box blanks comprising two cutter heads geared to operate in unison, one having two relatively short segmental knives, the ends of which are spaced apart circumferentially of the head a distance equal to the length of a flap which is not to be cut, and the other having a relatively long segmental knife adapted to overlap said short knives and having one of its ends circumferentially spaced from an end of one of said shorter knives, when the latter is at the cutting point, a distance equal to the length of a flap which is to be cut. 110

6. A machine for cutting the flaps of box blanks comprising two cutter heads geared to operate in unison, one having two relatively short segmental knives, the ends of which are spaced apart circumferentially of the head a distance equal to the length of a flap which is not to be cut, and the other 125

having a relatively long segmental knife adapted to overlap said short knives and having one of its ends circumferentially spaced from an end of one of said shorter knives, when the latter is at the cutting point, a distance equal to the length of a flap which is to be cut, said knives being ad-

justable relatively to one another about the axes of their respective heads.

In testimony whereof we hereunto affix our signatures.

ELLWOOD A. METZ.
THOS. S. FITCHETT.
